BUILT-UP STEP CONSTRUCTION

William J. Alcini, Royal Oak, Mich.

Application July 26, 1950, Serial No. 175,913

2 Claims. (Cl. 72—96)

1

This invention relates to building structures and, in particular, to step constructions.

One object of this invention is to provide a step construction wherein a flight of steps is built up of steps and saddles so constructed and arranged that after assembly, the flight of steps presents the appearance of a monolithic flight of steps which cannot be easily displaced and which will have unusually great strength and stability.

Another object is to provide a step construction composed of steps placed on spaced saddles, the steps and saddles being so constructed with invisible grooves or recesses as to be held together by a small amount of mortar which is substantially invisible in the finished flight of steps, and wherein the riser of one step overlaps the tread of the next lower step in such a way as to make the joint or crack substantially weather-proof, so that frost cannot get into the crack and damage either the steps or the saddles or displace one relatively to the other.

Another object is to provide a step construction of the foregoing character wherein the steps are of like construction so that the tread of each step is free from any visible projections or recesses, thereby enabling any step to be used as the top step and requiring only a single standard step unit for a flight of steps.

In the drawings:

Figure 1 is a front elevation of a flight of steps according to one form of the invention, with the right-hand corner broken away and in section along the line 1—1 in Figure 2;

Figure 2 is a side elevation of the flight of steps shown in Figure 1, with the central portion broken away and in section along the line 2—2 in Figure 1;

Figure 3 is a top perspective view of one of the saddles or step supports used in the flight of steps of Figures 1 and 2;

Figure 4 is a bottom perspective view of a step used in the flight of steps shown in Figures 1 and 2; and

Figure 5 is a top perspective view of the flight of steps of Figures 1 and 2 installed at the door of a house.

Hitherto, builders have found it difficult to obtain a satisfactory built-up step construction which is adaptable to different buildings and

which avoids the expensive monolithic step construction requiring setting up of forms and the mixing and pouring of cement, together with the use of skilled labor. Built-up step constructions previously devised have often been unsatisfactory, particularly in cold climates where frost works its way into the cracks in the steps and breaks off portions thereof, especially at the lower edges of the risers. Moreover, certain prior built-up step constructions have employed interlocking ribs and grooves which are not only easily damaged in transportation and assembly but also are hard to fit together and require careful workmanship. Finally, the component parts of such prior step constructions have frequently been displaceable relatively to one another after they have been supposedly completed, resulting in an unsatisfactory flight of steps.

The step construction of the present invention eliminates these difficulties and solves these problems by providing grooved saddles or side supports and grooved steps which are assembled with the riser of the one step slidably overlapping the rearward portion of the tread of the next lower step, with a small amount of mortar placed in the grooves to hold the steps in assembly with the saddles. When the flight of steps is so assembled, the component parts are not displaceable relatively to one another but present the appearance and have the action of a monolithic flight of steps. When great sidewise pressure is applied to a flight of steps constructed in accordance with the present invention, it slides bodily like a monolithic flight of steps and can be rolled over and over as a unit like a barrel.

Referring to the drawings in detail, Figures 1, 2 and 5 show a flight of steps, generally designated 10, according to one form of the invention, the flight 10 being shown as consisting of three steps but a greater or lesser number may obviously be used. The flight of steps 10 consists generally of a pair of spaced saddles or side supports 11 upon which steps 12 are mounted in the manner described below. The saddles 11 are in the form of concrete blocks or slabs of heights relatively greater than their widths. In other words, the saddles 11 resemble thick slabs of concrete set up on edge and provided with bottom surfaces 13, outer and inner sides 14 and 15 respectively, horizontally offset front surfaces 16

and vertically offset top surface portions 17 with a rear surface 18 running the full height of the saddle. Thus, the saddle 11 resembles a thick slab of concrete with one or more right-angled notches 19 cut out from the upper surface 20 of the slab, depending upon the number of steps in the flight. The top edge or surface 20 of each saddle thus consists of two or more vertically offset top surface portions 17 interconnected by one or more front portions 16. The saddles 11 are constructed in rights and lefts, Figure 3 showing a left-hand saddle. The outer top edge 21 of each saddle is preferably relatively sharp but the inner top edge 22 of each saddle is in the form of a downwardly and inwardly sloping rabbet or groove (Figure 3) for receiving the mortar by which the steps 12 and saddles 11 are held in assembly.

Each of the steps 12 is a single type, and all are interchangeable with one another so that any step may serve as the top step without exposing any grooves or projections and without presenting any unusual appearance. Each step consists of a flat elongated tread 23 of plate-like form having a rounded front edge 25 and a flat rear edge 27 (Figure 2). The rounded front edge 25 overlaps the riser 28, the front surface 29 of which is vertical and the rear surface 30 inclined upwardly and rearwardly from the bottom edge 31 of the riser 28. The bottom edge 31 is generally flat but is provided with an elongated groove 32 which joins corresponding grooves 33 (Figure 4) in the bottom edges 34 of the step sides 35. The grooves 32 and 33 are substantially at right angles to one another since the sides 35 are likewise at right angles to the risers 28. The outer surfaces 36 of the sides 35 are substantially vertical, whereas the inner surfaces 37 thereof are inclined upwardly and inwardly from the bottom edges 34. The grooves 32 and 33 are so located that they at least partially overlap the grooves 22 in the saddles 11 (Figure 1) so that the mortar filling 38 (Figure 1) will enter both sets of grooves and interlock them. Elsewhere, the mortar is in a thin layer 39, as explained in connection with the operation of the invention. The tread 25 of each step 12 has relatively flat upper and lower surfaces 40 and 41 respectively which are substantially parallel with one another, and the side edges 42 of each tread 25 are rounded (Figures 1 and 4) so as to slightly overhang the sides 35. The rearward edge surfaces 43 of the sides 35 are flat and substantially vertical.

In the operation of the invention, the operator assembles a pair of right and left-hand saddles 11 at the proper spacing with the top grooves 22 facing upward and inward (Figure 1) and in the proper locations, such as beneath the door sill 45 of a building 46 having a wall 47 against which the rear vertical surfaces 18 of the saddles 11 are placed. The operator first places the first step 12 in position with its rear surfaces 43 against the lower front saddle surfaces 16. He then carefully places a layer of mortar upon the top surfaces 17 of the saddle top 20, with the mortar extending over into the rabbets or grooves 22. He next places the second step 12 in position with the bottom edge 31 of its riser 28 slightly overlapping the upper surface 40 of the tread 25 of the first step 12 (Figure 2) and presses it downward upon the mortar so that the mortar is pushed upward into the grooves 32 and 33 (Figures 1 and 2) as well as downward into the saddle groove 22, resulting in the mortar portions 37 and 38 extending into the grooves (Figure 1) and the thin layers 39

between the steps and the top saddle surfaces 17. The operator continues to lay the steps 12 in the same overlapping manner described above, with the mortar disposed in the same way until he comes to the top step which is placed with its rearward tread edge surface 27 against the building wall 47 and substantially in alignment with the rearward vertical edge surfaces 18 of the saddles 11.

When the mortar hardens, it is found that the steps 12 and saddles 11 are so solidly interlocked that they are, for all practical purposes, united into an apparently monolithic flight of steps. The upper step 12 is as free from visible projections or recesses as the remaining steps, even though only a single standard step is used for all of the steps of the flight. Rain or frost cannot run in under the risers 28 because the thin layer of mortar (Figure 2) at this location completely fills the crack which would otherwise occur at that place. After the mortar has solidified, any attempt to push or roll over the steps results in the entire flight 19 being moved bodily. Indeed, the entire flight 19 can be rolled over and over like a barrel, as stated above.

What I claim is:

1. A built-up flight of steps comprising a pair of laterally-spaced saddles having stepped alternating horizontal and vertical top and front surfaces respectively, said top surfaces having elongated recesses along the inner edges thereof, inverted approximately box-shaped monolithic steps of substantially identical construction mounted upon said top saddle surfaces and against said front saddle surfaces, each of said steps having a tread portion on the top thereof, a riser portion at the front thereof and side portions at the opposite ends thereof, said riser portions and said side portions having grooves in their bottom surfaces extending upwardly therein, said side portion grooves registering at least partially with said recesses, a layer of binding material disposed between said steps and said top surfaces of said saddles, said material extending into said grooves and recesses in interlocking relationship with said steps and saddles, said layer of said material also extending from said grooves and recesses outwardly between the adjacent surfaces of said steps and saddles, the major part of each tread portion being exposed, the bottom of the riser portion of one step overlapping the rearward part of the tread portion of the next lower step.

2. A built-up flight of steps comprising a pair of laterally-spaced saddles having stepped alternating horizontal and vertical top and front surfaces respectively, said top surface having elongated recesses along the inner edges thereof, inverted approximately box-shaped monolithic steps of substantially identical construction mounted upon said top saddle surfaces and against said front saddle surfaces; each of said steps having a tread portion on the top thereof, a riser portion at the front thereof and side portions at the opposite ends thereof; said riser portions and said side portions having grooves in their bottom surfaces extending upwardly therein, said side portion grooves registering at least partially with said recesses, a layer of binding material disposed between said steps and said top surfaces of said saddles, said material extending into said grooves and recesses in interlocking relationship with said steps and saddles, said layer of said material also extending from said grooves and recesses outwardly between the adjacent sur-

faces of said steps and saddles, the major part of each tread portion being exposed, the bottom of the riser portion of one step overlapping the rearward part of the tread portion of the next lower step, the upper surface of the overlapped part of said tread portion being on substantially the same level as the exposed part thereof, said binding material layer also extending from said grooves and recesses outwardly between the bottoms of said riser portions and the thereby overlapped part of said tread portions in sealing relationship therebetween.

WILLIAM J. ALCINI.
